Inventor
Harry D. Morton

UNITED STATES PATENT OFFICE

HARRY D. MORTON, OF NEW YORK, N. Y.

SELF-LOCKING BOX.

Application filed November 17, 1925, Serial No. 69,581. Renewed January 16, 1928.

My invention has for its principal object the provision of such a box wherein, when the body and cover are pressed together, a locking is effected which renders said box tamper-proof.

In my application Serial No. 719,764, filed June 13, 1924, I disclose a three-piece box-locking device. In the present application I show a box provided with simplified and less 10 expensive locking means which may be more easily installed and which afford protection against theft of the contents of the box.

In the following specification I describe one form of self-locking box made in accordance 15 with my present invention, but it will be understood that various modifications and changes may be made therein without departing from the spirit of my invention and without exceeding the scope of my claims.

20 My invention will best be understood by reference to the accompanying drawings, in which I show portions of a self-locking box embodying my invention in the form and manner at present preferred by me, and in 25 which Fig. 1 is a plan view of a portion of a corner of such a box attached to which is a female locking member; Fig. 2 shows a portion of said box corner in section and said female locking member in elevation; Fig. 3 shows in 30 section on line 3—3 of Fig. 1 a portion of a telescopic box cover and box body permanently coupled together by said female locking member and a coacting male locking member, attached to said box cover—said locking 35 members being shown partly in section and partly in elevation; Fig. 4 shows a plan view of a male locking member adapted to be clinched to the cover of a box and to coact with the aforesaid female locking member.

40 Like reference characters indicate like parts throughout the drawings.

Referring to the drawings, 1 represents a portion of the body of a box attached to which is female locking member 2, provided with 45 prongs 3, 3^a, 3^b, etc., which prongs are adapted to pass through perforations formed in the box body and to be clinched on the inner side thereof. In order to add strength and rigidity to the female locking member 2, I may provide the same with one or more downwardly 50 bent edges, such as 4. Female locking member 2 is provided with an aperture 5, surrounded by a wall 6, preferably slotted to form segments 7, 7^a, 7^b and 7^c, whereby resilience 55 is imparted to said wall. Said locking member 2 is still further strengthened and the

locking position thereof with the coacting male locking member is brought close to the box cover by first downwardly pressing the metal of which member 2 is formed to produce 60 a cup-shaped portion 8, and then upwardly pressing the portion forming wall 6. Male locking member 9 is provided with prongs 10, 10^a and 10^b, which are adapted to pass through perforations formed in box cover 11, and to be 65 clinched on the inner side of said cover in such a position as to result in registration of the two locking members when the box body and cover are brought into telescopic relation. An aperture 12 is formed in box cover 11, through 70 which aperture the shank portion of male locking member 9 projects to permit of the engagement thereof with the female locking member. Formed in the end of such shank portion is flange 13, shown one-half in section 75 and one-half in elevation in Fig. 3. The outer edge of this flange is preferably turned upwardly to form a re-entrant angle, while the inner edges of segments 7, 7^a, 7^b and 7^c of wall 6 in female locking member 2 are turned in- 80 wardly and slightly downwardly. Thus, when the box body and box cover are brought into telescopic relation and pressed together, the segments 7, 7^a, 7^b, and 7^c are sprung outwardly by the pressure of flange 13 of the 85 male locking member. Further pressure carries said flange through aperture 5, whereupon these resilient segments spring back into place, surrounding flange 13, overlapping the edge thereof and effectually preventing subsequent separation of the locking members, and, therefore, of the box body and 90 box cover.

By forming male locking member 9 in one piece, I am enabled to greatly simplify its 95 manufacture and the operations of installing it upon the box cover. This unitary construction also possesses the advantage of preventing the contents of the box being damaged by entrance thereto of water, dust, etc. By constructing the female locking member in the manner shown in the drawings, I am enabled to bring the point of locking close to the top of the box body and to the box cover, thus permitting of the use of a short shank in the 100 male locking member and thereby adding to its strength and reducing the amount of metal required in its manufacture and the difficulty of drawing the shank and inner flange portions thereof.

105 On account of their light weight and relatively low cost, cardboard boxes are exten-

sively used in the shipping of many classes of merchandise. However, due to their inherent structural weakness, it is comparatively easy, while such boxes are in transit, to 5 open them and abstract their contents without leaving evidence of such tampering. By my invention, the box body and box cover are so firmly locked together that they cannot be separated except by mutilation so extensive as to amount to practical destruction 10 of the box, which becomes at once apparent.

On boxes of relatively large size, I prefer to install a locking device at each of the four corners. On smaller boxes, two locking devices at diagonally opposite corners may suffice; while on still smaller boxes, such as are employed in the shipment of jewelry and the like, the female locking member may be attached to opposite walls of the box body 20 and completely span its width. The form and construction of my present locking device and the location thereof within the box render it practically immune from tampering by any implement which might be applied thereto. My invention has the further advantage of strengthening the inherently weak walls of a cardboard box body, thereby adding 25 to the value of such boxes for shipping purposes.

30 What I claim as new and desire to secure by Letters Patent of the United States is:

1. A box comprising a body and a cover constructed and arranged to be placed in telescopic relation, a hollow unitary member attached to the top of said cover, projecting therethrough and clinched thereto, and means attached to two adjacent walls of said body, and having a portion which spans two edges thereof and a part of the intervening space 35 therebetween, and coacting with said unitary member to effect a permanent locking of said body and cover.

2. A box comprising a body and a cover constructed and arranged to be placed in telescopic relation, a unitary member having a flanged shank end and attached to the top of said cover by prongs extending therethrough, and means clinched to two adjacent walls of 45 said body and having a portion which spans two edges thereof and a part of the intervening space therebetween and coacting with said flanged end to effect a permanent locking of 50 said body and cover.

3. A box body having clinched to two of its adjacent walls a member, some portion of 55 which spans two of said walls and a part of the intervening space therebetween and provided with an aperture surrounded by a resilient wall and a box cover having clinched thereto an annular unitary member with an inwardly projecting portion constructed and 60 arranged to enter said aperture and to coact with said resilient wall to effect a permanent locking of said box body and box cover when the same are brought into telescopic relation. 65

4. A self-locking telescopic box comprising a body member and a cover member, unitary locking means attached to the top of the cover member and projecting inwardly therefrom, and means attached to two adjacent walls of 70 the body member for reinforcing the said body member and for coacting with said unitary locking member to permanently couple said body and cover members.

5. A self-locking telescopic box comprising 75 a body member and a cover member, unitary locking means projecting inwardly from the cover member and provided with prongs extending through the top of said cover member and clinched thereto, and means provided with prongs extending through two walls of 80 said body member and clinched thereto reinforcing said body and coacting with said unitary locking means to permanently couple said body and cover members.

6. In a self-locking box, a cover member provided with a unitary locking element projecting through the top thereof and clinched thereto and a body member provided with a locking element clinched to two adjacent 90 walls thereof and characterized by the fact that when said body and cover members are brought into telescopic relation, said locking elements coact to produce a permanent coupling of said cover and body within the box so 95 formed.

7. In a box, a cover member, a unitary locking element mounted upon the top thereof, a body member, and a corner reinforcing element mounted upon said body member and coacting with said unitary locking element to permanently couple said cover and said body upon the bringing of the same into telescopic relation and the applying of pressure therebetween.

HARRY D. MORTON.
